UNITED STATES PATENT OFFICE.

EDMUND BECKER, OF WASHINGTON, DISTRICT OF COLUMBIA.

METHOD OF AND APPARATUS FOR RELEASING PROJECTILES FROM MOVING CARRIERS.

1,332,022.

Specification of Letters Patent. Patented Feb. 24, 1920.

Application filed August 26, 1918. Serial No. 251,419.

To all whom it may concern:

Be it known that I, EDMUND BECKER, a citizen of the United States, residing at Washington, District of Columbia, have invented new and useful Improvements in Methods of and Apparatus for Releasing Projectiles from Moving Carriers, of which the following is a specification.

Dropping bombs from a flying aeroplane is a complex operation and the hitting a target from a great height is uncertain and erratic, and efficiency can only be expected from low flying, within easy range of the anti-aircraft guns.

The present invention comprises a method of and apparatus for dropping projectiles from a moving carrier, the method comprising releasing the projectile, releasing a counter-weight arranged to travel in the opposite direction from the direction in which the projectile is deflected by the momentum of the carrier, and causing said counter-weight to come in contact with the projectile to counteract or offset the momentum of the projectile and to cause it to fall by the force of gravity; the invention further comprises an organization of apparatus elements adapted to perform the above process consisting of means for supporting a projectile upon a moving carrier, a counter-weight arranged in proximity to the projectile, means for maintaining the counter-weight at a given tension and releasing means for the counter-weight operable by the release of the projectile to cause said counter-weight to move in a direction opposite to that imparted to the projectile by the momentum of the moving carrier, the counter-weight and the projectile being arranged relatively to each other so that the counter-weight will come in contact with the projectile to offset or overcome the horizontal momentum of the projectile; all as more fully hereinafter set forth and as claimed.

The present method of releasing projectiles from a moving carrier is particularly adapted for use in dropping bombs from aeroplanes, dropping sacks of mail from aeroplanes and dropping mail sacks from moving trains. When a bomb or other device is released from an aeroplane or other carrier there are two forces acting upon it, the force of gravity and the momentum of the bomb caused by the movement of the carrier. The object of the present invention is to overcome the second mentioned force

and cause the bomb to fall in a substantially perpendicular direction as if the aeroplane from which it is being dropped were in a state of rest.

A practical embodiment of the invention is represented in the accompanying drawings forming a part of this specification, in which similar characters of reference indicate corresponding parts in all views.

Figures 1 and 2 are diagrams of the physical laws involved; Figs. 3 and 4 the apparatus before and after release; Fig. 5 the plan of the cradle of the bomb; Fig. 6 its elevation; Fig. 7 a part of the apparatus showing bomb, cradle and striker before release; Fig. 8 the same as Fig. 7, but after release; Fig. 9 a hook of the cradle in perspective.

In all the drawings, the respective directions of motion are indicated by arrows Y, Z. Bombing is subservient to the three following physical laws:

First law.—A bomb B, Fig. 1, dropped from an aeroplane flying horizontally in the direction Y, Z, does not fall in the straight vertical line a, b, but describes the parabola a, c, T, which is a component of its momentum at the instant of its release with the gravity $\frac{1}{2}g+2$, and this parabola will vary according to the weight of the bomb, the horizontal velocity of the aeroplane and the duration of the fall.

Second law.—When, Fig. 2, two bodies B and B', of equal mass and flying horizontally on line 1, 2 with equal velocity one toward the other meet on line 3, 4, their progress will be instantaneously stopped, and if the rebound of their contact is absorbed by their compressibility, they will fall to earth respectively along the vertical straight lines a, b, and a', b'.

Third law.—But, to stop body B, another body B' of the same mass and velocity is not required, because Mv can be reacted against by mV , that is: a smaller mass actuated by a proportionally greater velocity:

$$M : m :: V : v$$

On the second and third laws (the third being a corollary of the second), my bomb releasing apparatus is founded, whereby the momentum of the bomb being neutralized, its fall in a straight vertical line follows.

I have applied the third law for two purposes: 1st, to keep down the mass of B', thereby reducing the weight of the appa-

ratus and diminishing its momentum which, in this case, acts contrary to its intended action; 2d, to make the same apparatus suitable for a greater range in sizes of bombs.

5 The bomb-releasing apparatus, Figs. 3, 4, 5, 6, 7, 8, consists principally of the following parts: the bomb B suspended to latch-bar F L pivoted on *p*, counter-striker B' on bent lever C D pivoted on P, and the

10 two springs *s* and *S*.

As perfect elastic bodies rebound after impinging, the face of counter-striker B' is overlaid with compressible, shock-absorbing material (cork or cushion) so as to act

15 as a pusher rather than as a hammer; the same deadening could also be applied to the bomb itself, but it would unnecessarily complicate its making.

Fig. 3 shows the apparatus ready for release;

20 Fig. 4 shows the apparatus after release. In these two figures the elements of the apparatus fixed to and parts of the body of the aeroplane are shown in dotted lines.

25 Fig. 3 shows bent lever C D compressed by spring *S*, and caught by latch L of bar F L; the bomb B is suspended to F L by rope H, and by its weight keeps the apparatus armed, and acts as the trigger of its

30 own release.

When, as shown by Fig. 4, the rope H is cut at *w*, *x*, spring *s*, in tension, will pull down the latch L, release CD and the

35 striker B', driven by relaxed spring *S*, will

counteract the horizontal momentum of B. The center of B in Fig. 3, before release, is shown at the height *t*, while in Fig. 4 it has lowered to *u* at the instant of striking; this distance *t*, *u* is necessary to meet the

40 conditions of the second precited law, Fig. 2, viz: a free falling body struck normally along the line of its axis of motion.

Striker B' is actuated by the resilience of relaxed spring *S*, the power of which can be varied in two ways: 1st, turning in either direction the screw E, which by its end-face-plate *e* permits to tune the compression of *S* to the most delicate degree; 2d,

50 replacing *S* by a lighter or a heavier spring. Tables have been prepared to indicate to the bomber the compression and the spring required for every and each condition.

To arm the apparatus, see Fig. 3, the bomb B, hung by rope H to rings *i* and *k*, 55 pulls down the end F of bar F L to rest on shelf 9 of the frame; plate *e* having been screwed backward, spring *S* has been reduced to its minimum of compression; lever CD of striker B' is pivoted toward *e* until 60 snapped by latch L and *e* being screwed forward to the distance indicated by the tables, the apparatus is ready for action.

When, see Fig. 4, the cord H is cut at *w*, *x*, the bar F L free from the weight of 65 the bomb B and pulled by the spring *s*, in

tension, liberates lever CD and striker B' stops the forward momentum of bomb B as it begins to fall.

I have chosen the release as operated by the cutting of the rope H, this being more 70 simple to establish, describe and illustrate, but any other suitable mode of suspension of the bomb and of quick release could be substituted.

The top end D of lever CD is stopped by 75 lug *g*, on frame of the aero, wherein a buffer R is housed to furnish a small margin in the penetration of the blow and absorb the recoil of the blow.

To better and more clearly connect my 80 invention and its basic principles, I have shown in Figs. 1, 2, 3 and 4 the bomb B and its striker B' as spheres, the center of gravity of the sphere being also its center of figure; but in Figs. 5, 6 and 7 the appa- 85 ratus takes a more practical form, and the sphere of B is replaced by a cylinder and that of B' by a prismatic hammer with a concave face which fits the convexity of the bomb as shown in Figs. 5 and 6; in Figs. 7 90 and 8, to simplify the drawing, B' is shown as a blade without thickness; also, as we are considering here the use of bombs of great bulk and weight, the ring *k* of lever FL has been replaced by the winch K oper- 95 ated by crank *o* or any other mechanical power.

As, to conform to the prepared tables, the force of the reaction is to be uniform, reliable and constant for each bomb of a 100 given caliber and weight, the bomb has to be made an integral part of the flying aeroplane until liberated to fall unrestrained through space, until at the level *u*, it is struck in such manner that it is reacted 105 upon normally to the vertical and the horizontal axes of its center of gravity, the cradle V has been added as an essential though independent adjunct of the releasing apparatus.

The cradle V is cylindrical in shape and encircles not more than seven-sixteenths ($\frac{7}{16}$) of the circumference of the bomb, Fig. 5 shows it at 6; turned out and widened to offer an easier entrance for the bomb. It 115 is hung to and rigidly braced to the frame of the aeroplane by straps 5; an opening U at the back is provided for B' to strike the bomb, and six (6) inverted hooks *n*, with projecting ends as shown on Fig. 9, 120 are placed on the inside, at top and bottom and at center and sides; the bomb, the top of which is tapered to enter the cradle from below, is provided, with belts *m*, at heights corresponding to hooks *n*, shown by 125 Fig. 9 in perspective. Belt *m* could be replaced by any other adequate loop, catch, or pocket.

The bomb B, see Fig. 7, having been trans- 130 ferred from the bomb-store of the aero-

plane, by means of rope H on winch K, to the cradle V, is pulled up to engage belts m into hooks n, until snugly housed in place.

5 It is then ready for the arming of the apparatus and the operation proceeds as explained for Figs. 3 and 4; the rope being cut at w w, the bomb, see Fig. 8, falls from t to u, where, disconnected from hooks 10 n, its horizontal momentum is eliminated by the counter-blow of B'.

It is obvious that the radii and the heights of cradles V shall agree with the corresponding dimensions of the bombs.

15 I claim:

1. The method of dropping projectiles from a moving carrier which comprises releasing the object, simultaneously releasing a counter-weight adapted to travel in the opposite direction to that of the carrier, and causing said counter-weight to come in contact with said object to overcome the momentum of the object caused by the movement of the carrier.

25 2. The method of dropping bombs from an aeroplane which comprises releasing the bomb simultaneously, releasing a counter-weight adapted to travel in the opposite direction to that of the aeroplane, and causing 30 said counter-weight to come in contact with said bomb to overcome the momentum of the bomb caused by the movement of the aeroplane.

3. In combination with a moving carrier, 35 an object releasing apparatus comprising supporting means, a counter-weight positioned with respect to the object, means for maintaining the counter-weight under tension, releasing means for the counter-weight 40 operable by release of the object to cause the counter-weight to move in a direction opposite to the direction of travel of the moving carrier and to come in contact with the object.

45 4. In combination with an aeroplane, a bomb releasing apparatus comprising bomb supporting means, a counter-weight positioned with respect to the bomb, means for maintaining the counter-weight under tension, releasing means for the counter-weight 50 operable by release of the bomb to cause the counter-weight to move in a direction opposite to the direction of travel of the aeroplane and to come in contact with the bomb.

55 5. In combination with an aeroplane, a bomb releasing apparatus comprising supporting and releasing means for the bomb, a counter-weight arranged in proximity to the bomb, a pivoted supporting member for 60 said counter-weight, means for maintaining pressure upon the opposite end of said pivoted member, and operating means to cause said pivoted element to respond to said pres-

sure when the bomb is released whereby the counter-weight is moved in the direction opposite to the direction of travel of the aeroplane and is brought into contact with the bomb to overcome its momentum.

6. An apparatus for dropping bombs from a moving aeroplane which comprises bomb 70 supporting means, a counter-weight disposed near the bomb, pivoted supporting means for the counter-weight, a spring arranged upon one end of said pivoted supporting means and adapted to move the counter-weight in a direction opposite to the path of travel of the aeroplane, means for normally maintaining the supporting element and counter-weight in inoperative position, and means for releasing the pivoted supporting member upon release of the bomb and causing said counter-weight to come in contact with the bomb to offset the momentum in the bomb caused by the travel of the machine.

7. An apparatus for releasing bombs from moving aeroplanes which comprises a pivoted supporting member for said bomb, a counter-weight arranged near the bomb, supporting means for said counter-weight, 90 means for maintaining pressure upon the counter-weight, said pressure being adapted to move the counter-weight in a direction opposite to the direction of travel of the machine, a latch carried by said pivoted bomb supporting element adapted to engage said counter-weight support, said latch being adapted to be disengaged upon release of the bomb whereby the pressure exerted upon said supporting element causes the counter-weight to move in a horizontal direction and to come in contact with the bomb to overcome its momentum caused by the movement of the aeroplane.

8. An apparatus for releasing bombs for 105 moving aeroplanes which comprises a pivoted supporting member for said bomb, a counter-weight arranged near the bomb, supporting means for said counter-weight, means for maintaining pressure upon the counter-weight, means for adjusting said pressure, said pressure being adapted to move the counter-weight in a direction opposite to the direction of travel of the machine, a latch carried by said pivoted bomb 110 supporting element adapted to engage said counter-weight support, said latch being adapted to be disengaged upon release of the bomb whereby the pressure exerted upon said supporting element causes the counter-weight to move in a horizontal direction and to come in contact with the bomb to overcome its momentum caused by the movement of the aeroplane.

EDMUND BECKER.
